To all whom it may concern.

Be it known that I, GEORGE E. VAN SISE, a citizen of the United States, residing at Brooklyn, in the county of Kings and State of New York, have invented a certain new, original, and ornamental Design for Badges or Emblems, of which the following is a specification.

In the accompanying drawing the figure illustrates an elevation of the badge or emblem embodying my design.

My said design is intended for a society insignia to be embodied in badges, or emblems, and it consists of a representation of three owls perched upon a ribbon, the ribbon being draped as shown, with its middle

portion elevated above the two side portions, which are similar to each other, and the owls perched upon said ribbon, the middle owl on the elevated portion. The letters "I. O. O." are arranged on the ribbon, one beneath each owl.

What I claim is:
